UNITED STATES PATENT OFFICE.

JOHN B. FARRAR, OF BRADFORD, MASSACHUSETTS.

BOOT OR SHOE.

SPECIFICATION forming part of Letters Patent No. 267,745, dated November 21, 1882.

Application filed May 26, 1882. (No model.)

To all whom it may concern:

Be it known that I, JOHN B. FARRAR, of Bradford, county of Essex, State of Massachusetts, have invented an Improvement in Boots and Shoes, of which the following description, in connection with the accompanying drawings, is a specification.

In the manufacture of a boot or shoe in accordance with my invention I take a piece of sole-leather of sufficient thickness to form the inner and covering soles, and instead of channelling the same for the reception of stitches, as has been done, I split the said sole from end to end, forming two soles, one of which is a counterpart of the other, and one of which serves as the inner sole to receive the stitches, while the other serves as the covering-sole. This covering-sole is applied to the inner sole after the same has been united with the welt-sole, and after the stitching of the outer sole, by means of suitable paste or cement, preferably made water-proof, and then the soles, with the covering-sole in place, are beat out in any usual way, thus leaving for contact with the stocking the grain side of the covering-sole split off from the inner sole.

Figure 1 represents in side elevation a shoe embodying my improvements; Fig. 2, a partial section thereof across the ball of the shoe; Fig. 3, a partial section across the shank; and Fig. 4, the piece of sole-leather from which are made the inner and covering soles, the said piece of leather being shown as partially split to form the two soles.

A piece of sole-leather of sufficient thickness for an inner and a covering sole is split (see Fig. 4) to form an inner sole, *a*, and a covering-sole, *b*, the latter having the grain-face. The inner sole, *a*, laid upon the last, has the upper *c* drawn over it, filling *e'* is inserted between the edges of the upper, the welt-sole *e* is applied, and it and the upper and inner sole are

united by stitches *f*, extending through and through them. The outer sole, *g*, properly channeled, is then applied and stitched to the 45 welt-sole outside the upper by the stitches *h*, and to the upper and inner sole at the shank of the shoe by the stitches *m*. The channel-flap of the outer sole hides the stitches *h m* outside of the shoe. Having provided the 50 covering-sole *b* with suitable cement or paste, preferably water-proof, the said sole is placed in the shoe to cover the inner sole, and the shoe and soles are then subjected to the beating-out operation, which molds the covering-sole to the inner sole and covers the stitches *h m*, leaving the smooth grain-face of the sole-leather covering-sole exposed to view in the shoe and to receive against it the stocking.

I do not broadly claim an inner sole channeled about its edge to receive stitches, the flap of the channel being thereafter turned down to cover the stitches.

I claim—

That improvement in the manufacture of 65 boots and shoes which consists in splitting a piece of sole-leather to remove entirely from it its grain-face, thus forming an inner sole and a grain-faced covering or lining sole, then uniting the inner sole with the upper and the 70 outer sole, and reapplying upon the face of the inner sole the said grain-faced covering-sole, cementing the same to the inner sole to cover the stitches or fastenings therein, leaving the grain-face of the said covering-sole uppermost, 75 all as shown and described.

In testimony whereof I have signed my name to this specification in the presence of two subscribing witnesses.

JOHN B. FARRAR.
